UNITED STATES PATENT OFFICE.

WILLIAM E. JOHNSON, OF ROCK ISLAND, ILLINOIS, ASSIGNOR TO ROCK ISLAND PLOW COMPANY, OF ROCK ISLAND, ILLINOIS, A CORPORATION OF ILLINOIS.

HAND-LEVER FOR RIDING-CULTIVATORS.

No. 903,139.

Specification of Letters Patent.

Patented Nov. 3, 1908.

Application filed January 28, 1907. Serial No. 354,402.

To all whom it may concern:

Be it known that I, WILLIAM E. JOHNSON, a citizen of the United States of America, and resident of Rock Island, Illinois, have 5 invented a certain new and useful Improvement in Hand-Levers for Riding-Cultivators, of which the following is a specification.

My invention relates to improvements in hand levers for riding cultivators of that 10 particular type in which the shovel gangs are raised and lowered by means of hand levers, and in which the depth at which the shovels operate is varied by means of interlocking connections between the said hand 15 levers and the swinging racks or segments to which are connected the springs that are employed for assisting in raising the shovel gangs, as well as for holding the gangs out of the ground.

20 In a cultivator of this character, it has been found that if the operator inadvertently releases the racks from the levers while the said racks or segments are in an intermediate position, the sudden jerk of the springs 25 will then throw the released racks or segments forward suddenly and with considerable force. This may not only prove injurious to the structure of the cultivator, but is also calculated to annoy the operator.

30 Generally stated, therefore, the object of my present invention is the provision of an arrangement that will prevent the racks from being released from the hand levers while in intermediate positions, and which 35 will permit of such release only when the racks are in their extreme forward or rearward positions, thus precluding all danger of these racks or segments being suddenly jerked into their forward positions by the 40 tension of the strong springs which not only assist to some extent in the final lifting of the shovel gangs, but which also serve to yieldingly hold the said gangs in their elevated or raised positions.

45 To the foregoing and other useful ends, my invention consists in matters herein-after set forth and claimed.

In the accompanying drawings, Figure 1 is a perspective of a cultivator, hand lever, 50 lifting arrangement embodying the principles of my invention. Fig. 2 is a front elevation of the construction shown in Fig. 1. Fig. 3 is a side elevation showing a hand lever and its pivoted segment or rack in an intermediate position. Fig. 4 is a similar

view showing the hand lever and its segment or rack swung back to the extreme rearward position thereof. Fig. 5 is a rear elevation of the mechanism and construction shown in Fig. 4. Fig. 6 is a view similar to Fig. 3, 60 but showing the hand lever and its segment or rack somewhat farther to the front. Fig. 7 is an enlarged detail section on line 7—7 in Fig. 3. Fig. 8 is an enlarged detail section on line 8—8 in Fig. 3. Fig. 9 is a detailed 65 perspective view of the latch employed for preventing an unlocking of the hand lever while its rack or segment is in an intermediate position.

As thus illustrated, the side or frame-bar 70 A is secured to the casting B which has an upwardly extending ear or bracket b. It will be seen that this ear or bracket b is provided with a curved or hook-shaped portion b¹. The hand lever C is pivotally mounted 75 upon the bolt c and provided with a short arm c¹. This bolt extends through the ear or bracket b, and serves also to support the rocking or pivoted rack or segment D. It will be seen that the lever has a locking bolt 80 c² which is suitably connected with and operated by a hand piece c³. The said locking bolt is adapted to engage any one of the notches d in the said rack or segment, whereby the said lever may be locked in various 85 positions relatively to the said rack or segment. The latch or locking device E is pivoted to the rack or segment at e and provided with a lateral end-portion e¹ adapted to engage the outer edge of the portion b¹. The 90 other end-portion e² of said latch is connected by a rod e³ with the projecting outer end-portion of the locking bolt c². In this way, the said locking bolt cannot be withdrawn from one of the notches d without tilting the 95 latch E about its pivotal point e. It will be seen that the tilting of the said latch E cannot occur except when the rack or segment B is in the position shown in Fig. 6, or in the position shown in Fig. 4, owing to the formation of the outer edge of the portion b¹. Consequently, the lever cannot be released from the said rack or segment at any intermediate 100 position of the latter.

The lever and rack or segment are thrown 105 into the position indicated in Fig. 6 to lower the shovel gang, and to the position shown in Fig. 4 to maintain the shovel gang in an elevated position. The rod F connects the lever arm c¹ with the means for lifting the 110

shovel gang, and the curved link G connects the rack or segment with the spring H, which latter has its forward end connected with some suitable portion of the cultivator frame. 5 The point g at which the said link G connects with the said rack or segment is below the center in Fig. 4, and consequently the spring H tends to hold the shovel gang out of the ground. Should the hand lever be released 10 from the rack or segment while in this position, the tension of the spring cannot jerk the rack or segment forward. On the other hand, when the lever is thrown to the position shown in Fig. 6, the rack or segment is then nearing its extreme forward position, and hence a releasing of the lever at this time would not result in an undesirable and violent jerking forward of the said rack or segment by the tension of the spring. In 15 other words, the relation of the lever to the segment can only be changed or varied when the latter is at its extreme forward or rearward position, and in either case the unlocking of the hand lever from the rack or segment cannot result in a sudden jerking forward of the latter. In this way, I have remedied a difficulty which has heretofore given the driver or operator considerable annoyance and trouble. 20 25 30 What I claim as my invention is:

1. In a device of the class described, a pivoted rack, a hand lever, means for locking the hand lever in different positions relatively to

the said rack or segment, a spring hitched to the rack or segment, and means for locking 35 the said rack or segment against disconnection from the said lever while the rack or segment is in an intermediate position.

2. In a device of the class described, the combination of a hand lever, a pivoted rack 40 or segment, means on the said lever for locking the same in different positions relatively to the said rack or segment, a spring to the forward pull of which the said rack or segment is subject, a latch connected to hold the locking means on the lever in engagement with the said rack or segment, and a stationary portion adapted to engage said latch to prevent unlocking of the lever except when the said rack or segment is in its forward or 45 rearward position.

3. In a device of the class described, the combination of a hand lever, a pivoted rack 55 or segment, means on the hand lever for locking the same in different positions relatively to the said rack or segment, a spring exerting a pull on said rack or segment, and means for preventing unlocking of the lever before the rack or segment reaches a position of rest under the tension of the spring. 60

Signed by me at Rock Island, Illinois, this 5th day of January, 1907.

WILLIAM E. JOHNSON.
